UNITED STATES PATENT OFFICE.

GUSTAVE M. NELL, OF CLEVELAND, OHIO, ASSIGNOR TO THE CLEVELAND ROCK DRILL COMPANY, OF CLEVELAND, OHIO.

VALVE STRUCTURE FOR ROCK DRILLS.

Application filed November 9, 1922. Serial No. 599,949.

The present invention is directed to improvements in valve structures for rock drills.

The primary object of the invention is to provide novel means for locking the valve stem against accidental rotation, and at the same time permitting the valve to be easily and quickly disassembled for inspection.

A further object of the invention is to provide means for cushioning the movement of the valve during its reciprocation. It is well known that in drills of this type the valve is rapidly reciprocated and during this reciprocation the ends thereof strike the end caps of the casing, and to cushion the impact of blows upon the respective caps, means are provided for yieldably holding the caps in their operative positions.

With these and other objects in view, as will appear as the description proceeds, the invention consists in the novel features of construction, combination of elements, and arrangement of parts hereinafter to be fully described, and particularly pointed out in the appended claim.

In the accompanying drawing:

Figure 1 is a longitudinal sectional view through the device.

Figure 2 is an end view of the valve casing.

Figure 3 is a similar view of the other end of the same.

Referring to the drawing 1 designates the cylinder of a rock drill in which is mounted for reciprocation the hammer 2. Mounted upon the cylinder 1 is a valve casing 3 having a longitudinal chamber 4 into which motive fluid is introduced through the port 5. The motive fluid, after being properly distributed by the valve 6 mounted for reciprocation in the chamber 4, is conducted to the hammer chamber 7 for reciprocating the hammer 2, as is customary. The valve 6 is of the spool type and is provided with a longitudinal axially arranged bore 9. Since no claim is to be made for the specific construction of the valve 8 in this application, it is not thought necessary to give a detailed description of the operation thereof.

It will be observed that the chamber 4 extends through the casing 3, and in order to close the open ends thereof after the valve 6 has been placed in said chamber, caps 10 and 11 are provided for engagement in the re-

spective open ends, as clearly shown in Fig. 55 1 of the drawing.

The caps 10 and 11 are of such dimensions as to closely fit the ends of the chamber 4, and in order to limit the movement thereof inwardly they are provided with flanges 12 60 and 13, respectively. These flanges are of such construction that they not only limit the inward movements of the caps, but co-operate with the cylinder in such manner that they are held positively against rotation.

The flange 12 of the cap 10 is provided with a lug 14, which is adapted to engage the longitudinal groove 15 formed in the cylinder 1, and when thus engaged it will be 70 obvious that the flange 12, and thus the cap 10 is held against rotation, but may be readily removed upon sliding the same outwardly. The cap 11 has its flange 13 provided with a shallow recess 16, which is 75 adapted to interlock with the lug 17 formed on the cylinder 1, thereby holding the cap 11 against rotation, but permitting the same to be conveniently removed when desired. The cap 11 is further provided with a cavity 80 18 in which is formed a seat 19, the purpose of which will appear later.

A longitudinal bore 20 is formed through the cap 11, and has its outer end opening into the cavity 18. It is necessary that the 85 caps 10 and 11 be held firmly seated in the open ends of the chamber 4, and to accomplish this in a simple and efficient manner, the cap 10 is provided with an integral inwardly directed stem 21. This stem is of 90 such length as to pass through the bore 20 of the cap 11 and have its outer end projected beyond said cap, said stem being threaded for a certain distance of its length, and engaged on the threaded portion is a nut 95 22 in which is formed a seat 23, the purpose of which will later appear. This stem of course passes through the axial bore 9 of the valve 6, and since the valve is mounted for reciprocation in the chamber 4 it necessarily follows that said valve slides upon the stem as its reciprocates.

A coil spring 24 encircles the threaded end of the stem 21, and has its inner helix provided with a head 25 adapted to engage in 105 the seat 19, while the head 26 formed upon its outer helix engages in the seat 23 of the nut 22, as clearly illustrated in Fig. 1 of

the drawing. Thus it will be seen that upon manipulating the nut 22 in one direction that the spring 24 will be compressed to desired degree to hold the caps 10 and 11 properly seated in the open ends of the chamber 4, and owing to the presence of the heads 25 and 26 accidental rotation of the nut 22 is prevented.

It is a well known fact that rock drills of the percussive type are subjected to considerable vibration when operating, and consequently the valve parts become loose, which when unnoticed affects the efficiency of the drill. This defect is overcome in the present invention by interlocking the caps 10 and 11, respectively, and the cylinder, through the medium of the lug 14 and groove 15 and the recess 16 and lug 17.

It will further be observed that impact of the blows of the valve incident to striking the respective caps during its reciprocation will be cushioned owing to the presence of

the coil spring 24, which will permit slight sliding movement of the respective caps.

What is claimed is:

The combination with a cylinder, of a casing carried thereby, a valve mounted for reciprocation therein and having an axial bore, caps fitting directly in the ends of the casing, one cap having an integral stem which passes through said bore and the other cap, said cylinder having a relatively long longitudinal groove and lug disposed, respectively, adjacent the ends of the casing, said caps having, respectively, a peripheral lug and recess for slidably and detachable interlocking engagement, respectively, with the groove and lug of the cylinder, and means engaged with one end of the stem for holding both caps yieldably engaged in the ends of the casing.

In testimony whereof I have hereunto set my hand.

GUSTAVE M. NELL.
